Primary Examiner — T. Chase Nelson*Assistant Examiner* — Ania Aman(74) *Attorney, Agent, or Firm* — The Webb Law Firm(57) **CLAIM**

The ornamental design for a transport vehicle, as shown and described.

DESCRIPTION

FIG. 1 is a front view of a transport vehicle showing my new design;

FIG. 2 is a rear view thereof;

FIG. 3 is a left side view thereof;

FIG. 4 is a right side view thereof;

FIG. 5 is a top view thereof; and,

FIG. 6 is a perspective view thereof.

A bottom view is omitted because it is plain and unornamental and forms no part of the subject matter of the claimed design.

The portions of the transport vehicle shown in broken lines form no part of the claimed design.
